UNITED STATES PATENT OFFICE.

GEORGE WASHINGTON GREENER, OF STREATOR, ILLINOIS, ASSIGNOR OF
ONE-HALF TO JAMES L. PRINGLE, OF SAME PLACE.

THILL-COUPING.

SPECIFICATION forming part of Letters Patent No. 333,518, dated January 5, 1886.

Application filed February 10, 1885. Serial No. 155,473. (No model.)

To all whom it may concern:

Be it known that I, GEORGE W. GREENER, a citizen of the United States, residing at Streator, in the county of La Salle and State 5 of Illinois, have invented certain new and useful Improvements in Vehicle-Thill-Coupling Supports; and I do hereby declare that the following is a full, clear, and exact description of the same, reference being had to 10 the annexed drawings, making a part of this specification, and to the letters and figures of reference marked thereon.

Figure 1 of the drawings is a perspective view of my invention, and Fig. 2 a sectional 15 view thereof.

The present invention has relation to certain new and useful improvements in vehicle-thill-coupling supports; and it consists in the details of construction substantially as shown 20 in the drawings, and hereinafter described and claimed.

In the accompanying drawings, A represents the fore axle of a vehicle, and B the clip, to which the thill-iron C is detachably connected. The clip B is secured to the fore axle 25 A by the clamping-plate *a* and nuts *b*, the plate having on its forward end a keeper, D, formed with a beveled end, *c*. This keeper D is for the purpose of holding the flat curved spring E in position, as shown in dotted lines, Fig. 2, when not in use. The spring E is attached at one end to the clip B, and extends 30 up some distance and bent around, as shown at *d*, and thence extends down below the clip 35 and is curved, as shown at *e*, thus giving the spring increased strength and power, and when brought in position, as shown in full lines, bears with the necessary force against the eye *f* of the thill-iron to hold it in the required elevated position. The clip B has two 40 forwardly-extending eye-plates, G, between which the eye *f* of the thill-iron C is connected and held by a coupling-pin, H. The eye-plates G, and also the eye *f* of the thill-iron, have 45 key-slots *g* to receive the keyed end *h* of the pin H.

When it is desired to connect the thill-iron C to the clip B, the eye *f* of said thill-iron is placed between the plates G and brought in 50 position, so that the key-slot therein will be

in line and register with the key-slots in the plates, when the pin H may be readily inserted.

After the pin has been inserted, as above described, the pin is firmly and securely 55 tightened by the cam *i* upon the outer side of one of the plates G, this being accomplished by turning the pin in the proper direction, so that the keyed end thereof will ride over the face of the cam, the keyed end of the pin and 60 the cam holding the thill without the necessity of the usual nut, while the spring will prevent the thill-iron from rattling.

When the spring is disconnected from the keeper or catch hereinbefore described, it will 65 bear against the eye of the thill-iron with a force necessary to hold it in position, so that there will be no rattling, but admit of the thill being readily moved up and down as desired.

In the detachment of the thill-iron the 70 spring is first made to engage with the keeper, which is done by simply pressing it in a direction toward the axle, the beveled end of the keeper allowing the spring to freely ride over it and automatically engage therewith, 75 as shown in dotted lines. The eye of the thill-iron is now brought in position so that the key-slot therein and the key-slots in the eye-plates will be in line and register, when the pin may be withdrawn and the thill re- 80 moved.

When the vehicle is in use, the pin cannot possibly come out by reasons of its keyed end and the cam also, because the key-slots are not in line to admit the keyed end passing 85 through them. The thills are required to be raised much higher than necessary for use in order to bring the key-slots in line, thus doing away with the necessity of nut and wrench, yet making a positively safe coupling, both 90 easy, convenient, and handy to adjust.

Having now fully described my invention, what I claim as new, and desire to secure by Letters Patent, is—

1. In a vehicle-thill-coupling support; the 95 combination, with a coupling-pin provided with a keyed end, of the thill-iron and clip having key-slots, as shown, and a cam upon one of the plates formed with the key-slot, against which the keyed end of the pin bears 100

to tighten it, substantially as and for the purpose set forth.

2. In a vehicle-thill-coupling support, the combination, with the thill-iron and clip having the clamping-plate terminating at its forward end in a catch or keeper formed with a beveled end, of a flat curved spring connected at one end to the clip and extending upward and around and downward below the clip, substantially as and for the purpose specified.

3. In a vehicle-thill-coupling support, a thill-iron having an eye with key-slot, a clip having eye-plates with corresponding key-slots, and a cam upon one of said plates, in

combination with a keyed end coupling-pin, a catch or keeper formed on the clamping-plate, and a curved spring connected at one end to the clip and extending upward and around and downward below the thill-iron and clip, substantially as and for the purpose set forth. 20

In testimony that I claim the above I have hereunto subscribed my name in the presence of two witnesses.

GEORGE WASHINGTON GREENER.
